United States Patent Office.

CHARLES G. HARINGTON, OF NORTHLVILLE, MICHIGAN.

Design No. 4,076, dated May 31, 1870.

DESIGN FOR A SCHOOL SEAT AND DESK.

The Schedule referred to in these Letters Patent and making part of the same.

To whom it may concern:

Be it known that I, CHARLES G. HARINGTON, of Northville, in the county of Wayne and State of Michigan, have invented a new and original Design in a School Seat and Desk; and I do declare that the following is a true and accurate description thereof, reference being had to the accompanying photograph, being a part of this specification.

The nature of my design relates to the construction and ornamentation of the cast-iron standards which form the ends and receive the wooden top and

front of the desk, special notice being called to the front board of the desk, and to that part of the standard which is angled, as at A, to fit the outline of the sitter in front thereof.

I claim as my invention—

The design for a school-desk standard, as shown.

CHARLES G. HARINGTON.

Witnesses:

SAMUEL J. SPRAY,
A. F. DUNLOP.
